US0D1045259S

(12) **United States Design Patent** (10) **Patent No.:** **US D1,045,259 S**
(45) **Date of Patent:** **** Oct. 1, 2024**

(54) **PET TRAINING DEVICE**

(71) Applicant: **Weiqa Zhang**, Biyang (CN)

(72) Inventor: **Weiqa Zhang**, Biyang (CN)

(**) Term: **15 Years**

(21) Appl. No.: **29/885,076**

(22) Filed: **Feb. 20, 2023**

(30) **Foreign Application Priority Data**

Nov. 10, 2022 (CN) 202230751095.6

(51) **LOC (14) Cl.** **30-99**

(52) **U.S. Cl.**

USPC **D30/199**

(58) **Field of Classification Search**

USPC D10/78, 80, 104.1; D13/168, 154; D14/137, 217, 218; D30/144, 151, 152,

D30/160, 199

(57) **CLAIM**

The ornamental design for a pet training device, as shown and described.

DESCRIPTION

FIG. 1 is a first perspective view of a pet training device showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the pet training device that form no part of the claimed design.

1 Claim, 8 Drawing Sheets
